BRACKET FOR ATTACHING ELECTRICAL FIXTURES AND CONDUIT AND OTHER CONDUITS TO ROOF AND FLOOR DECKING

Marcello R. Austin, Kalamazoo, Mich.

Application June 20, 1949, Serial No. 100,282

7 Claims. (Cl. 248—49)

1

This invention relates to improvements in bracket for attaching electrical fixtures and conduit and other conduits to roof and floor decking.

The principal objects of this invention are:

First, to provide a simple inexpensive bracket for attaching electrical wiring conduit and fixtures or other appurtenances to that form of roof and floor decking used in building construction consisting of interlocking panels of U-shaped cross section.

Second, to provide a bracket which is easily formed and which has springable engagement with the panels of a roof decking.

Third, to provide a bracket which is easily and quickly installed at any position along a panel of a roof deck.

Other objects and advantages relating to details of my bracket will be apparent from a consideration of the following description and claims.

The drawings, of which there is one sheet, illustrate a preferred form of my bracket operatively associated with the panels of a roof or floor deck and various types of conduits and fixtures supportable thereby.

Fig. 1 is a fragmentary perspective view of a particular type of roof or floor decking commonly used in building construction with my bracket mounted thereon.

Fig. 2 is a fragmentary cross sectional view taken longitudinally of the deck panel along the plane of the line 2—2 of Figs. 1 and 3.

Fig. 3 is a fragmentary cross sectional view taken transversely of the deck panel along the plane of the line 3—3 of Fig. 2.

Fig. 4 is a plan view of my bracket with the fixture attaching plate in place thereon.

Fig. 5 is a fragmentary cross sectional view similar to Fig. 3 but illustrating a conduit supported by the bracket.

Roofs and floors of some large buildings are commonly formed by laying what is known as roof decking on supporting beams and girders. In Fig. 1, I have illustrated one form of roof construction commonly used and consisting of a series of interlocking panels 1 having an inverted U-shaped cross section with side flanges 2 and 3. The left side flanges are provided on their lower edge with outturned rims 4 and right flanges 3 are provided on their lower edge with return bend folds 5 and laterally extending rims 6. The panels are assembled on suitable structural supports in an interlocking relation with the left rims 4 supported on the right rim 6 of the preceding panel and interlocking in the U-shaped

2

fold 5. My bracket is designed to be mounted on this type of roof or floor decking.

My bracket consists of a strip of metal formed by stamping, bending or otherwise to provide a central base 7 with depending arms 8 and 9 on the ends thereof. The base is longitudinally slotted as at 10 and is provided with side flanges 11 which serve to stiffen the base.

The left arm 8 extends approximately perpendicularly with respect to the base and is provided on its lower end with an outturned flange 12 terminating in a hook 13. As illustrated, the flange 12 and hook 13 are arranged to fit around and grip the return fold 5 and rim 6 of one panel of the decking with the arm 8 extending vertically inside of the left arm 2 of the next adjacent decking panel. The right arm 9 of my bracket extends at a slight outward angle from the perpendicular to the end of the base 7 and is substantially shorter than the left arm 8 so that the lower end of the right arm will fit within the decking panel and rest upon the top surface of the return fold 5. Preferably the arms 8 and 9 are of such a length that the top edges of the flanges 11 will bear against the under side of the panel 1.

The bracket is made of metal which is sufficiently springable so that the right arm 9 will be displaced in pressing it into the deck panel and will then spring outwardly to tightly engage the top of the fold 5.

Preferably each bracket is furnished with a rectangular anchoring plate 14 which fits between the flanges 11 and defines a pair of tapped holes 15 for the reception of screws 16. The screws are operative to secure various types of fixtures and hangers to the bracket.

In Figs. 1 to 3 I have illustrated an electrical outlet box 17 secured to the bracket by means of the screws 16. Electrical conduits can be attached to and supported by the outlet box in the normal manner. In Fig. 5 I have illustrated a U-shaped hanger 18 secured to the bracket by the screws 16 and serving to support a length of pipe or conduit 19. Other types of fixtures and hangers may be attached to my bracket as desired as will readily be appreciated.

My hanger is light and inexpensive to manufacture and can be quickly snapped in place at any desired position on a decking panel. If necessary the bracket can be slid along the panel a short distance to bring it into a more desirable position. Attention is called to the fact that the several decking panels 1—1 may be erected with various spacings resulting in different spacings

between the right and left flanges thereof. In Fig. 1 a wide spacing is illustrated at 20 and a close spacing is illustrated at 21. Regardless of the variations in spacing the springable and angular character of the right arm 9 of my bracket is operative to securely support the right end of the bracket.

Having thus described my invention what I claim as new and desire to secure by Letters Patent is:

1. A bracket for attachment to deck panels having U-shaped cross section with interlocking rims on the bottoms of the flanges thereof, said bracket comprising, a generally U-shaped stamping having one arm extending perpendicularly with respect to the base of the stamping and another arm extending angularly outwardly from the perpendicular to the base of the stamping, said angularly disposed arm and base being relatively springable, an outturned flange on the end of said first arm, a hook on the end of said flange adapted to embrace the interlocking rims of two of said panels, stiffening flanges turned upwardly on the sides of said base, said base having a longitudinally extending slot formed therethrough, and a fixture anchoring plate fitting between said stiffening flanges and forming a plurality of tapped apertures registering with said slot, said other arm being substantially shorter than said perpendicular arm by an amount approximately equal to the thickness of the hook on said perpendicular arm.

2. A bracket for attachment to deck panels having U-shaped cross section with interlocking rims on the bottoms of the flanges thereof, said bracket comprising a generally U-shaped strip of metal having one arm extending generally perpendicularly with respect to the base of the strip and another arm extending angularly outwardly from the perpendicular to the base, said angularly disposed arm being relatively springable, an outturned flange on the end of said first arm, a hook on the end of said flange adapted to embrace the interlocking portions of two of said panels, and stiffening flanges turned upwardly on the sides of said base, said base having a longitudinally extending slot formed therethrough, said other arm being substantially shorter than said perpendicular arm by an amount approximately equal to the thickness of the hook on said perpendicular arm.

3. A bracket for attachment to deck panels having U-shaped cross section with interlocking rims on the bottoms of the flanges thereof, said bracket comprising a generally U-shaped stamping having one arm extending generally perpendicularly with respect to the base of the stamping and another arm extending angularly outwardly from the perpendicular to the base of the stamping, said angularly disposed arm being relatively springable, an outturned flange on the end of said first arm, and a hook on the end of said flange adapted to embrace the interlocking portions of two of said panels, said base having a longitudinally extending slot formed therethrough, said other arm being substantially shorter than said perpendicular arm by an

amount approximately equal to the thickness of the hook on said perpendicular arm.

4. A bracket for attachment to deck panels having U-shaped cross section with interlocking rims on the bottoms of the flanges thereof, said bracket comprising, a generally U-shaped strip of metal having a pair of arms extending from the base of the strip, one of said arms extending angularly outwardly from the perpendicular to the base, said angularly disposed arm and base being relatively springable, an outturned flange on the end of the other of said arms, and a hook on the end of said flange adapted to embrace the interlocking portions of two of said panels, said one arm being substantially shorter than said other arm.

5. A bracket comprising a generally U-shaped body having one arm extending perpendicularly with respect to the base of the body and another arm extending angularly outwardly from the perpendicular to the base, said angularly disposed arm and base being relatively springable, an outturned flange on the end of said first arm, an upwardly and inwardly-turned hook on the end of said flange, and stiffening flanges turned upwardly on the sides of said base, said base having a longitudinally extending slot formed therethrough, said other arm being substantially shorter than said perpendicular arm by an amount approximately equal to the thickness of the hook on said flange.

6. A bracket comprising a generally U-shaped stamping having one arm extending perpendicularly with respect to the base of the stamping and another arm extending angularly outwardly from the perpendicular to the base of the stamping, said angularly disposed arm and base being relatively springable, an outturned flange on the end of said first arm, an upwardly and inwardly turned hook on the end of said flange, and stiffening flanges turned upwardly on the sides of said base, said base having a longitudinally extending slot formed therethrough, said other arm being substantially shorter than said perpendicular arm.

7. A bracket comprising, a generally U-shaped body having a pair of arms extending from the base of the body, one of said arms extending angularly outwardly from the perpendicular to the base, said angularly disposed arm and base being relatively springable, an outturned flange on the end of the other of said arms, and an upwardly and inwardly turned hook on the end of said flange, said base having a longitudinally extending slot formed therethrough, said one arm being substantially shorter than said other arm.
